UNITED STATES PATENT OFFICE.

JOHN W. HOUGHTON AND THOMAS W. HARVEY, OF HUNTINGTON, WEST VIRGINIA,
ASSIGNORS TO STEEL PRODUCTS CO., OF HUNTINGTON, WEST VIRGINIA, A COR-
PORATION OF WEST VIRGINIA.

LOADING-MACHINE ATTACHMENT.

Application filed April 14, 1921. Serial No. 461,324.

To all whom it may concern:

Be it known that we, JOHN W. HOUGHTON and THOMAS W. HARVEY, citizens of the United States, residing at Huntington, in the county of Cabell and State of West Virginia, have invented new and useful Improvements in Loading-Machine Attachments, of which the following is a specification.

10 This invention relates to improvements in machines for loading coal and other material, and consists essentially of improvements in the type of machine disclosed by the patents of Francis K. Holmested, No. 1,290,200, of January 7, 1919, and 1,291,522, of January 14, 1919, and also illustrated and described in the application of John W. Houghton and Thurston W. Mitchell, Serial No. 428,077. The improvement consists specifically in applying to the feed shovel or nose at the forward end of the inclined portion of a conveyer and cooperating with a reciprocating feed bar, forwardly projecting material-dislodging means, which in part is movable and effects a fall of the material relatively to the bulk of material operated upon and a drop thereof onto the feed shovel or nose. The primary object of the invention is to provide means in connection with the feed shovel or nose at the forward extremity of a conveyer which will easily penetrate the material to be loaded and facilitate loading of the material relatively to the shovel end or nose when the latter is withdrawn from and reset 35 in operative position or penetration relatively to the material to be loaded.

In the accompanying drawing:

Fig. 1 is a side elevation of the feed shovel or nose at the lower end of a conveyer, showing the improvement applied thereto.

Fig. 2 is a top plan view of the feed shovel or nose as shown by Fig. 1 with the improved attachment on opposite sides thereof, one side of the feed shovel or nose and one attachment being illustrated in horizontal section.

Fig. 3 is a detail perspective view of the simplified form of the attachment.

Fig. 4 is a view similar to Fig. 3, showing 50 a modification of the attachment.

As in the patented machines of Francis K. Holmested and the machine disclosed by the pending application of Messrs. Houghton and Mitchell hereinbefore referred to, a con-

veyer 5 is comprised in the cooperating components of the loading machine, said conveyer having opposite beams 6 which incline downwardly a suitable distance and connect with, or have applied thereto, a feed shovel or nose, generally indicated by the numeral 8. From the lower feeding shovel or nose 8 upwardly over the inclined portions of the beams 6 and continuing over the horizontal portion of said beams is a pan or trough 9, preferably formed of sheet metal of suitable thickness and firmly attached to the beams at opposite side edges. Suitable conveying means, such as cross bars or lags 10, have close movement upwardly over the pan or trough 9 and are actuated by suitable mechanism forming no part of the present improvement. The feed shovel or nose 8 is of a practically unitary structure, or, is composed of a metal strip or sheet of suitable dimensions bent over at opposite sides to 75 provide U-shaped housings or angular guides 11 with their inner opposite sides fully open. This shovel end or nose extends downwardly from the forward terminals of the beams 6 and for a greater portion of its length is 80 straight and at the same inclination as the beams. The front extremity of the feed shovel or shovel end or nose is horizontally flat, as at 12, and the terminating end thereof is beveled off, as at 13, in a downward 85 and forward direction. Between the horizontal straight extremity 12 of the feed shovel or shovel end and the remaining straight inclined portion of the latter, a bend 14 is formed which is gradual and obviously necessary to dispose the said extremity 12 horizontally, and whereby the forward extremity of the shovel end or nose may be caused to practically penetrate the coal or material to be loaded or operated 95 upon by the machine. The curved bend of the shovel end or nose is regularly carried out fully across the said end or nose and including the housings 11, and reciprocatingly mounted on and closely engaging the upper 100 surface 15 of the shovel end or nose is a feed bar 16 which is angular in cross section, the opposite ends of the said bar being freely movable in and covered by the housings or enclosing guides 11. The feed bar 16 has a 105 forward reduced edge 17 and a rear vertically straight side 18 disposed towards the movable elements of the conveyer. The rear

straight side of the bar 16 provides a feeding shoulder to push coal or other material upwardly over the smooth surface of the shovel end or nose. To the opposite ends of the feed bar 16 flexible connections 19 are attached and composed of a plurality of links pivotally jointed to permit the connections to freely move over the shovel end and conform to the configuration of the upper surface of the plate, which is regularly continued within the housings. The connections 19 are given uniform and regular reciprocating strokes by actuating means, preferably consisting of slide blocks 21 mounted in the outer portions of the lower inclined extremities of the beams 6, the said slide blocks having pitmen 20 pivotally attached thereto and operated by suitable driving mechanism to uniformly and simultaneously reciprocate the blocks 21 and actuate the flexible connections 19 and regularly move the feed bar 16 over the shovel end or nose, the said feed bar 16 being movable over the shovel end or nose such distance as to bring up the material being loaded into operative engagement with the conveying means.

The foregoing structure is particularly disclosed by the application of Messrs. Thurston and Mitchell, hereinbefore noted, and the improvement consists of a material-displacing attachment, shown in detail by Figs. 3 and 4, and comprising a shank 22 conforming in longitudinal contour to the outer side of the shovel end or nose and having extending therethrough a plurality of openings 23 to receive attaching bolts and nuts or analogous devices 24, which project outwardly from the opposite sides of the outer walls of the housings 11 for the flexible connections 19, as clearly shown by Fig. 2. The displacing attachment has its forward end beveled, as at 24, to facilitate penetration thereof into the mass of material to be loaded, and in the simplified form of the improvement shown by Fig. 3, a single displacing means is shown and consists of a drag arm 25 pivotally secured at its lower end 26 to the forward extremity of the attachment, the arm being free to move upwardly and downwardly at its rear extremity. The rear end 27 of the arm 25 is shaped to form an abutment to operate upon the material adapted to be drawn towards the shovel end or nose 8 and the feed bar 16. The arm 25 is prevented from falling below a certain predetermined level by a stop pin 28 projecting outwardly from the shank 22, and at such elevation that a part of the free end 27 of the arm is always held elevated above the upper edge of the said shank 22 of the attachment. The forward pivoted extremity of the arm 25 is rounded and fits in a correspondingly curved socket 29, and where this socket passes out through the upper edge of the forward extremity of the at-

tachment a transversely straight shoulder 30 is formed to bear upon the upper straight edge of the arm 25 and limit the upward movement of said arm and also brace the latter when performing its function in drawing material rearwardly towards the shovel end or nose 8 and the reciprocating feed bar 16.

In the modified form of the attachment as shown by Fig. 4, a plurality of the arms 25 are applied to the outer side thereof in a manner similar to that shown by Fig. 3, and the shank 22 is made correspondingly longer, it being understood that any number of the arms 25 may be employed as found necessary.

One of the attachments in either form is adjustably applied to each outer side of the shovel end or nose 8 and projects beyond the front terminal of the latter, the single arm attachment shown by Fig. 3 being so applied that its arm will stand in advance of the front terminal of the shovel end or nose, and the modified form of the attachment having a plurality of arms being also so applied that all of the arms will be in advance of the front terminal of the shovel end or nose.

When the shovel end or nose is pushed forwardly into the bulk of material to be loaded, the beveled front ends 24 of the shanks 22 become imbedded in the material, and also the arms 25, the latter being depressed by engagement with the material to their lowest level and engage the stop means therefor, said stop means in the modified structure being part of the shank, as at 31, the shank being constructed of such width in the modified structure as to accommodate the application of a plurality of the arms 25 thereto. After the shovel end or nose 28 and the attachments have been set or applied to the material to be loaded, as just explained, the feed bar 16 is caused to operate and draw the material upwardly towards and into engagement with the conveyer elements. When the shovel end or nose is withdrawn or moved rearwardly for the purpose of resetting or repenetrating the same relatively to the material to be loaded, the one or more arms 25 of the attachments are immediately drawn upwardly by the engagement of the material with the rear abutment ends 27 of the arms, and by this means the material is drawn rearwardly towards the shovel end or nose and feed bar 16 and over onto the latter, and the bulk of material that may be standing above the arm or arms 25 is caused to fall and also drop over onto the forward extremity of the shovel end or nose for engagement with the said feed bar, with material advantages in facilitating the loading operation.

The improved attachment may be applied to any machine now in use having co-operating devices such as the reciprocating feed bar 16 or any other analogous feed

means and will be found exceptionally advantageous in disposing the material to be loaded for engagement by the feed means for a conveyer.

5. What is claimed as new is:

1. The combination with the shovel end of a conveyer of a loading machine having means for moving material to the conveyer, of rigid material-displacing attachments applied to opposite sides and in part projecting in advance of the terminal of the shovel end, the attachments having movable arms on the outer sides wholly above the lower edges of said arms and adapted to penetrate the material and displace the latter when the shovel end is withdrawn from the material.

2. The combination with the shovel end of a conveyer having means for moving material upwardly thereover to the conveyer, of rigid material displacing means having a fixed association with relation to opposite sides of and in part in advance of the front extremity of said shovel end, the said material-displacing means being provided with arms pivoted at their forward lower ends above the lower edges of the arms and having a free gravitating movement at their rear ends, the said arms being located above and any portions thereof prevented from moving below the lower edges of said means.

3. The combination with the shovel end of a conveyer having means for moving material upwardly thereover to the conveyer, of rigid material-displacing means applied to opposite sides and in part in advance of the front extremity of the shovel end and provided with gravitating arms having their rear ends free to move upwardly and downwardly and controlled as to their downward movement by stop means, the said arms dur-

ing their operations being wholly held at all times above the lower edges of the displacing means.

4. The combination with the shovel end of a conveyer having means for moving material upwardly thereover to the conveyer, of rigid material-displacing means applied to opposite sides and in part in advance of the front extremity of the shovel end and provided with gravitating arms having their rear ends free to move upwardly and downwardly and controlled as to their downward movement by stop means, but at all times wholly held above the lower edges of the displacing means, each attachment being longitudinally adjustable with relation to the shovel end.

5. The combination with a shovel end at the front extremity of a conveyer having means for moving material thereover into engaging position by the conveyer, of a rigid displacing attachment secured to each side and projecting in advance of the front extremity of the shovel end, the attachments having fixed penetrating forward ends and arms pivoted at their front lower extremities and free to move upwardly and downwardly at their rear ends the arms being at all times held above the lower edges of the displacing attachments, means being provided to limit the upward and downward movements of the arms.

In testimony whereof we have hereunto set our hands in presence of two subscribing witnesses.

JOHN W. HOUGHTON.
THOMAS W. HARVEY.
